UNITED STATES PATENT OFFICE.

ADOLPH KASTOR, OF NEW YORK, N. Y.

DESIGN FOR A KNIFE-HANDLE.

SPECIFICATION forming part of Design No. 31,298, dated August 1, 1899.

Application filed June 2, 1899. Serial No. 719,148. Term of patent 14 years.

To all whom it may concern:

Be it known that I, ADOLPH KASTOR, a citizen of the United States, residing at New York, in the county of New York and State of New York, have invented and produced a new and original Design for Knife-Handles, of which the following is a specification, reference being had to the accompanying drawings, forming part thereof.

5. In the drawings forming part of this specification, Figure 1 is a plan view of one side of a knife-handle, showing my new design; Fig. 2, a front edge view thereof; and Fig. 3, a view similar to Fig. 1, showing the opposite side.

As shown in the drawings, the leading or material feature of my design consists of the segmental notches or recesses A in the front

edge of one side of the handle, two of which are employed, and a similar segmental notch 20 or recess B in the front edge of the opposite side, the sides C of the handle being of the usual form.

Having fully described my invention, I claim as new and desire to secure by Letters 25 Patent—

The design for a knife-handle herein shown and described.

In testimony that I claim the foregoing as my invention I have signed my name, in presence of the subscribing witnesses, this 17th day of May, 1899.

ADOLPH KASTOR.

Witnesses:

F. A. STEWART,
V. M. VOSLER.
